UNITED STATES PATENT OFFICE.

BARTE J. GRIFFIN, OF SPRINGFIELD, MASSACHUSETTS.

VALVE.

1,394,895.

Specification of Letters Patent.

Patented Oct. 25, 1921.

Application filed February 24, 1920. Serial No. 360,677.

To all whom it may concern.:

Be it known that I, BARTE J. GRIFFIN, a citizen of the United States, and resident of Springfield, in the county of Hampden and 5 State of Massachusetts, have invented a new and useful Improvement in Valves, of which the following is a specification.

My invention is directed to improvements in that class of valves in which a normally 10 closed inlet valve is opened by pressure exerted thereon due to the admission of liquid from the supply side of the valve where it will over-balance the pressure tending to hold the valve closed and will thus open the 15 valve.

My invention is particularly directed to novel means for controlling the escape of the liquid pressure which holds the valve open so that the valve may close, said escape controlling means being regulable for causing the valve to close after different predetermined open intervals.

A practical embodiment of my invention is represented in the accompanying drawings, in which,

Figure 1 represents the valve in longitudinal central section.

Fig. 2 represents a transverse section taken in the plane of the line II—II of Fig. 1.

Fig. 3 represents a transverse section taken in the plane of the line III—III of Fig. 1.

Fig. 4 represents a transverse section taken in the plane of the line IV—IV of Fig. 1.

Fig. 5 represents a transverse section taken in the plane of the line V—V of Fig. 1.

The valve casing is denoted by 1, and is herein shown of cylindrical form in cross section.

The inlet port is denoted by 2 and the discharge port by 3. The service pipe 4 is secured to the inlet end of the casing by any suitable couplings 5. The discharge pipe 6 is secured to the discharge branch 7 of the casing by any suitable coupling 8.

The end of the casing opposite the inlet end is provided with a suitable head comprising the outer head member 9, screw-threaded into the end of the casing and the inner head member 10 fitted to the bore 11

of the outer head member. A member 12 is screw-threaded on to the outer head member 9 and serves to retain the auxiliary valve operating handle 13 in engagement with the

top of the stem 14 of the said auxiliary valve 15. The inlet valve 16 is connected to its actuating piston 17 by means of the hollow stem 18. This piston, together with the casting forms a piston chamber 19.

The valve seat 20 for the inlet valve 16 is connected to the inner head member 10 by a tube 21 located within the hollow valve stem 18. The bore of this tube 21 is provided with a seat 22 for the manually operated auxiliary valve 15, the stem 14 of which projects upwardly through the bore of the tube 21 and through a suitable stuffing box 23 in the head member 10, into engagement with the handle 13. The valve seat 20 is preferably provided with a three armed spider 24, terminating in a central lug 25 within the valve stem 18, to which the lower end of the tube 21 is screw-threaded. The valve stem 18 is provided with elongated slots 26 through which the arms of the spider 24 extend. Branch passages 27 lead through the valve seat and spider arm to the lower end of the bore of the tube 21, to open communication from the supply or inlet side of the valve 16 to the interior of the tube 21.

Branch passages 28 in the head member 10 lead from the upper end of the bore of the tube 21 into the piston chamber 19 for opening communication from the interior of the tube beyond the auxiliary valve 15 to the said piston chamber. A sleeve 29 projects from the head member 10, which sleeve surrounds and is spaced from the tube 21 leaving a passage 30. A port 31 through the wall of the valve stem 18 opens communication from the passage 30 to the interior of the casing on the discharge side of the inlet valve 16.

A restricted leakage passage 32 in the head member 10 leads from the piston chamber 19 to the passage 30 between the tube 21 and sleeve 29.

The piston chamber 19 is therefore always in open communication with the discharge side of the inlet valve through this restricted leakage passage, the passage 30 and the port 31.

I have provided means for regulating the size of this leakage passage, which means in the present instance is shown as a needle valve 33, screw-threaded in the head member 10 and provided with a suitable kerf 34

exposed within the bore 11 where the needle valve may be adjusted readily by removing the handle cap 12.

If so desired, a coil spring 35 may be introduced between the valve seat and the valve piston for assisting the water pressure in holding the inlet valve closed against its seat. Also a coil spring 36 may be introduced in the bore of the tube 21 between the auxiliary valve 15 and the lug 25 for assisting the water pressure in holding the auxiliary valve closed against its seat 22.

I preferably make the wall of the inlet valve seat convex as shown at 37 and I preferably make the wall of the inlet valve convex as shown at 38 so as to prevent any tendency of the valve to stick to its seat.

In operation, when it is desired to open the inlet valve 16, the operating handle 13 is either depressed or rocked. This movement will open the auxiliary valve 15 by forcing down the valve stem 14. The liquid will then pass through the passages 27, the bore of the tube 21 past the valve 15 and through the branch passage 28 into the piston chamber 19. The pressure exerted by this liquid on the inlet valve piston 17 will move the piston along the piston chamber in a direction to open the inlet valve 16, and thereby 30 permit the free passage of the liquid from the supply to the discharge. In the meantime, the liquid is permitted to escape from the piston chamber through the restricted leakage passage 32, the bore of the sleeve 29 and the 35 port 31 to the discharge. As soon as enough liquid has escaped to remove the over-balancing pressure on the inlet valve piston 17, the inlet valve 16 will automatically close. The period which the inlet valve may be 40 permitted to remain open may be regulated by restricting the leakage passage to a greater or lesser extent by screwing or unscrewing the needle valve 33.

It will thus be seen that I have provided 45 a very simple and efficient means for controlling the time which the inlet valve remains open and one which is easily regulable.

It is evident that this valve may be used 50 in many different ways such for instance as in connection with the flushing of water closets, the supply of water to a wash basin, etc.

It is also evident that various changes 55 may be resorted to in the construction, form and arrangement of the several parts without departing from the spirit and scope of my invention; hence I do not wish to be limited to the particular embodiment herein 60 shown and described, but

What I claim is:

1. A casing having inlet and discharge ports and a piston chamber, a normally closed inlet valve having a hollow stem provided with a piston slidable in the piston

chamber, a seat for the inlet valve, a passage leading through the valve seat and hollow stem from the inlet to the piston chamber, and a manually operated normally closed auxiliary valve for said passage. 70

2. A casing having inlet and discharge ports and a piston chamber, a normally closed inlet valve having a hollow stem provided with a piston slidable in the piston chamber, a seat for the inlet valve, a passage leading through the valve seat and hollow stem from the inlet to the piston chamber, a manually operated normally closed auxiliary valve for said passage, and a leakage passage leading from said piston chamber partly through said hollow stem into communication with said discharge port. 75 80

3. A casing having inlet and discharge ports and a piston chamber, a normally closed inlet valve having a hollow stem provided with a piston slidable in the piston chamber, a seat for the inlet valve, a passage leading through the valve seat and hollow stem from the inlet to the piston chamber, a manually operated normally closed auxiliary valve for said passage, and a regulable leakage passage leading from said piston chamber partly through said hollow stem into communication with said discharge port. 85 90 95

4. A casing having inlet and discharge ports and a piston chamber, a normally closed inlet valve having a hollow stem provided with a piston slidable in the piston chamber, a seat for the inlet valve, said seat having a tube located within the hollow stem and spaced for a distance therefrom, the passage through said tube communicating with both the inlet and piston chamber, and a manually operated normally closed auxiliary valve for said passage through said tube. 100 105

5. A casing having inlet and discharge ports and a piston chamber, a normally closed inlet valve having a hollow stem provided with a piston slidable in the piston chamber, a seat for the inlet valve, said seat having a tube located within the hollow stem and spaced for a distance therefrom, the passage through said tube communicating with both the inlet and piston chamber, a manually operated normally closed auxiliary valve for said passage through said tube, and a leakage passage leading from said piston chamber partly through said hollow stem around said tube into communication with said discharge port. 110 115

6. A casing having inlet and discharge ports and a piston chamber, a normally closed inlet valve having a hollow stem provided with a piston slidable in the piston chamber, a seat for the inlet valve, said seat having a tube located within the hollow stem and spaced for a distance therefrom, the passage through said tube communicating 120 125 130

with both the inlet and piston chamber, a manually operated normally closed auxiliary valve for said passage through said tube, and a regulable leakage passage leading from 5 said piston chamber partly through said hollow stem around said tube into communication with said discharge port.

7. A casing having inlet and discharge ports and a piston chamber, a normally closed inlet valve having a hollow stem provided with a piston slideable in the piston chamber, a valve seat, a head member, a tube located within the hollow stem and connecting the seat and head member, branch passages leading from the bore of the tube through the seat and head member to the inlet and piston chamber respectively, and a manually operated normally closed auxiliary valve for said bore.

- 20 8. A casing having inlet and discharge ports and a piston chamber, a normally closed inlet valve having a hollow stem provided with a piston slideable in the piston chamber, a valve seat, a head member, a tube located within the hollow stem and connecting the seat and head member, branch passages leading from the bore of the tube through the seat and head member to the inlet and piston chamber respectively, a manually operated normally closed auxiliary valve for said bore, and a leakage passage in said head member for said piston chamber.
- 25
- 30

9. A casing having inlet and discharge ports and a piston chamber, a normally closed inlet valve having a hollow stem provided with a piston slideable in the piston chamber, a valve seat, a head member, a tube located within the hollow stem and connecting the seat and head member, branch passages leading from the bore of the tube through the seat and head member to the inlet and piston chamber respectively, a manually operated normally closed auxiliary valve for said bore, and a regulable leak-

age passage in said head member for said piston chamber.

10. A casing having inlet and discharge ports and a piston chamber, a normally closed inlet valve having a hollow stem provided with a piston slideable in the piston chamber, a valve seat, a head member, a tube located within the hollow stem and connecting the seat and head member, branch passages leading from the bore of the tube through the seat and head member to the inlet and piston chamber respectively, a manually operated normally closed auxiliary valve for said bore, a sleeve extending from the head member, surrounding and spaced from the tube, a port in the hollow stem for bringing the interior of the sleeve into communication with the discharge side of the valve, and a leakage passage in said head member leading from the piston chamber to the interior of the sleeve. 50 55 60 65

11. A casing having inlet and discharge ports and a piston chamber, a normally closed inlet valve having a hollow stem provided with a piston slideable in the piston chamber, a valve seat, a head member, a tube located within the hollow stem and connecting the seat and head member, branch passages leading from the bore of the tube through the seat and head member to the inlet and piston chamber respectively, a manually operated normally closed auxiliary valve for said bore, a sleeve extending from the head member, surrounding and spaced from the tube, a port in the hollow stem for bringing the interior of the sleeve into communication with the discharge side of the valve, and a regulable leakage passage in said head member leading from the piston chamber to the interior of the sleeve.

placed closer to the interior of the sleeve. 85
In testimony that I claim the foregoing
as my invention, I have signed my name this
nineteenth day of February, 1920.

BARTE J. GRIFFIN
